(57) **ABSTRACT**

A unique foldable table comprises a collapse-preventing tabletop assembly, a plurality of extendable-leg assemblies releasably attached to the tabletop assembly, and a plurality of scissoring-arm assemblies attached to the extendable-leg assemblies, respectively. The collapse-preventing tabletop assembly has an automatic collapse-preventing system of clamps for automatically cross-interlocking the tabletop and the extendable-leg assemblies to prevent the unique foldable table from folding inwards and collapsing. The extendable-leg assemblies have: an automatic button-latching and button-releasing system of spring-loaded latches for automatically latching and automatically releasing the release buttons to simplify the cumbersome, two-handed table operation into an easy, one-handed table operation to eliminate the risk of personal injury; and an automatic leg-centering system of leg-centering clamps for automatically centering and clamping the extendable-leg assemblies to lock them in place.

**UNIQUE FOLDABLE TABLE HAVING
AUTOMATIC BUTTON-LATCHING AND
BUTTON-RELEASING SYSTEM,
AUTOMATIC LEG-CENTERING SYSTEM,
AND AUTOMATIC COLLAPSE-PREVENTING
SYSTEM**

BACKGROUND OF THE INVENTION

1. Field of the Invention

The present invention relates to a foldable table, which is easy, convenient, and safe to fold and unfold, and which is strong, durable, and safe to use. Particularly, the present invention relates to a foldable table having an automatic button-latching and button-releasing system, an automatic leg-centering system, and an automatic collapse-preventing system.

2. Description of the Prior Art

A number of foldable and collapsible tables and frames have been introduced. U.S. Pat. No. 2,618,524, filed Nov. 30, 1949, to C. Hoffmann; U.S. Pat. No. 3,646,895, filed Sep. 2, 1970, to Richard B. Campbell; U.S. Pat. No. 4,262,606, filed Jan. 2, 1979, to Hollis C. Hodson; U.S. Pat. No. 5,243,803, filed Nov. 30, 1992, to Tabata; U.S. Pat. No. 5,421,273, filed Mar. 14, 1994, to Yuan-Hsiung Lin; U.S. Pat. No. 5,435,510, filed Dec. 23, 1993, to Louis Wey; U.S. Pat. No. 5,645,259, filed Jun. 21, 1996, to Kao-San Chen; U.S. Pat. No. 5,865,127, filed Mar. 24, 1998, to Mark C. Carter; U.S. Pat. No. 5,884,566, filed Jul. 2, 1997, to Kao-San Chen; U.S. Pat. No. 6,026,751, filed Dec. 31, 1998, to Ming-Liang Tsai; U.S. Pat. No. 6,073,894, filed Mar. 18, 1998, to Kao-San Chen; U.S. Pat. No. 6,079,338, filed Aug. 23, 1999, to Chin-Chung Yeh; U.S. Pat. No. 6,125,769, filed Aug. 4, 1999, to Ting-sheng Tsai; U.S. Pat. No. 6,158,361, filed Apr. 30, 1999, to Edward Zheng; U.S. Pat. No. 6,193,308, filed Aug. 3, 1999, to Joo-Hwan Hwang; U.S. Pat. No. 6,199,489, filed Jan. 7, 2000, to Ting-Sheng Tsai; U.S. Pat. No. 6,234,089, filed Jun. 29, 1999, to Edward Zheng; U.S. Pat. No. 6,283,045, filed Jan. 24, 2000, to Satoshi Izumi; U.S. Pat. No. 6,505,565, filed Mar. 28, 2000, to Choi Sang Byung; U.S. Pat. No. 6,575,422, filed Dec. 18, 2000, to Edward Zheng; U.S. Pat. No. 6,640,730, filed Dec. 6, 2001, to Ming-Liang Tsai; U.S. Pat. No. 6,722,293, filed Sep. 26, 2002, to Yu-Shu Lee; U.S. Pat. No. 6,920,834, filed Feb. 7, 2003, to John A. Pehta; U.S. Pat. No. 6,929,230, filed Oct. 17, 2003, to Ming-Liang Tsai; U.S. Pat. No. 6,997,111, filed Oct. 31, 2003, to Paul Giegerich; U.S. Pat. No. 7,543,614, filed Mar. 13, 2007, to Robert W. Wise; and U.S. Pat. No. 7,604,289, filed Dec. 4, 2007, to Libin Chen disclose a variety of inventions related to foldable and collapsible tables and frames. The prior art has failed to solve many problems associated with such foldable and collapsible tables and frames, as follows:

No prior art offers or discloses any foldable table having automatic button-latching and button-releasing system, automatic leg-centering system, and automatic collapse-preventing system.

No prior art offers or discloses any automatic button-latching and button-releasing system. As a result, no prior-art table can be automatically activated to fold with a simple push of each of the release buttons of the table.

No prior art offers or discloses any automatic button-latching and button-releasing system. As a result, instead of an easy, one-handed operation, all the prior-art foldable tables require a cumbersome, two-handed operation to be folded.

To unlock each locking sleeve of the prior-art tables to fold them up, all the prior art requires two simultaneous actions of: a) Pressing the release button of one locking sleeve with one

hand, and b) At the same time, pressing the frame of the table downwards with another hand, to stretch the frame to keep the locking sleeve in an “unlocking position”.

All prior art requires the need to stretch the frames of the tables to unlock the tables each time the tables are folded. This results in quickly weakening the structural strength of and quickly shortening the service lifespan of the frames of the tables over time.

No prior art offers or discloses any automatic leg-centering system to automatically prevent the extendable-leg assemblies of all prior art from wobbling. As a result, the extendable-leg assemblies of all prior art wobble and quickly weaken the structural strength of and quickly shorten the service lifespan of the frames of the tables over time.

No prior art offers or discloses any automatic collapse-preventing system to strengthen the entire structure of the tables while in use. As a result, all prior art has experienced a decreased tolerance and durability of the structure of the tables as well as a shortened lifespan thereof.

No prior art offers or discloses any automatic collapse-preventing system to automatically cross-interlock the removable tabletop and all the extendable-leg assemblies of the tables to prevent the tables from folding inwards and, thus, collapsing. As a result, the prior-art tables are susceptible to accidental collapse and, thus, to the risk of personal injury.

In this respect, the unique foldable table of the present invention substantially departs from the conventional concepts and designs of the prior art, and in doing so provides a unique apparatus, which has an automatic button-latching and button-releasing system, an automatic leg-centering system, and an automatic collapse-preventing system, which can:

- (a) Automatically latch the release buttons of the table,
- (b) Automatically release the release buttons of the table,
- (c) Simplify a cumbersome, two-handed operation into an easy, one-handed operation,
- (d) Eliminate the needs for stretching the frame of the table while unlocking the table to offer ease of use, durability, and safety,
- (e) Automatically center and clamp the extendable-leg assemblies of the table to prevent the extendable-leg assemblies from wobbling,
- (f) Automatically cross-interlock the removable tabletop and the frame of the table to prevent the frame from accidentally folding inwards and collapsing and, thus, to prevent the risk of personal injury, and
- (g) Secure the removable tabletop of the table onto the frame of the table to prevent the frame from twisting and stretching while in use to strengthen the whole structure of the table while in use for substantially higher degrees of tolerance and durability.

Therefore, there exists a continuing need for a new, improved, easy-to-operate, and safe foldable table. In this regard, the present invention substantially fulfills this need.

**OBJECTS AND ADVANTAGES OF THE
INVENTION**

The present invention substantially departs from the conventional concepts and designs of the prior art. In doing so, the present invention provides a unique foldable table having many unique and significant features, automatic functions, and advantages, which overcome all the disadvantages of the prior art, as follows:

It is an object of the present invention to provide the unique foldable table having an automatic button-latching and but-

ton-releasing system, an automatic leg-centering system, and an automatic collapse-preventing system.

It is another object of the present invention to provide the automatic button-latching and button-releasing system for automatically latching the release buttons of the unique foldable table, and for automatically releasing the release buttons of the unique foldable table. The automatic button-latching and button-releasing system can be automatically activated whenever the buttons are pressed, and can be automatically deactivated whenever the table is folded.

It is a further object of the present invention to provide the automatic button-latching and button-releasing system for eliminating the simultaneous needs for using one hand to press the release buttons while using another hand to stretch the frames of the prior-art tables to unlock the prior-art tables at the same time.

It is an even further object of the present invention to provide the automatic button-latching and button-releasing system for simplifying a conventionally cumbersome, two-handed operation of folding the prior-art tables into a uniquely easy, one-handed operation, which requires only one simple push for each of the release buttons.

It is another object of the present invention to provide the automatic button-latching and button-releasing system for eliminating the needs for stretching the frames of the prior-art tables while unlocking the prior-art tables to offer ease of use, safety, and durability, and to eliminate the risk of personal injury.

It is yet another object of the present invention to provide the automatic leg-centering system for automatically centering and clamping the extendable-leg assemblies of the unique foldable table to strengthen the extendable-leg assemblies to prevent them from wobbling while in use.

It is yet another object of the present invention to provide the automatic collapse-preventing system for automatically cross-interlocking the removable tabletop and the frame of the unique foldable table to prevent the frame from accidentally folding inwards and collapsing and, thus, to eliminate the risk of personal injury.

It is still yet another object of the present invention to provide the automatic collapse-preventing system for automatically cross-interlocking the removable tabletop and the frame of the unique foldable table to prevent the frame from twisting and stretching while in use to strengthen the whole structure of the unique foldable table while in use for substantially higher degrees of tolerance and durability.

Other objects and advantages of the present invention will become apparent from a consideration of the accompanying drawings and ensuing description.

BRIEF DESCRIPTION OF THE DRAWINGS

FIG. 1A illustrates all the automatic functions performed by a unique foldable table having an automatic button-latching and button-releasing system, an automatic leg-centering system, and an automatic collapse-preventing system.

FIG. 1B illustrates a perspective view of the unique foldable table.

FIG. 2 illustrates an exploded perspective view of the locking sleeve and the automatic latch.

FIG. 3 illustrates a perspective view of an automatic leg-centering clamp.

FIG. 4A illustrates a perspective view of an automatic collapse-preventing system having collapse-preventing clamps.

FIG. 4B illustrates a perspective view of an automatic collapse-preventing clamp and a tabletop-locking post.

FIG. 5 illustrates an exploded perspective view of the locking sleeve and the automatic latch.

FIG. 6 illustrates a perspective view of an automatic leg-centering clamp.

FIG. 7 illustrates a hatching view of the automatic leg-centering clamp.

FIG. 8A illustrates a perspective view of a locking sleeve and an automatic latch in a button-latching position.

FIG. 8B illustrates a side view of the locking sleeve and the automatic latch in a button-latching position.

FIG. 9A illustrates a perspective view of the locking sleeve and the automatic latch in a button-releasing position.

FIG. 9B illustrates a side view of the locking sleeve and the automatic latch in a button-releasing position.

FIG. 10 illustrates a perspective view of a spring-loaded extendable-leg lock.

FIG. 11 illustrates an equivalent of collapse-preventing clamps.

FIG. 12 illustrates all the automatic functions performed by the unique foldable table.

FIG. 13 illustrates equivalents of a leg, an automatic leg-centering clamp, and an extendable leg.

FIG. 14 illustrates an equivalent of a collapse-preventing tabletop.

SUMMARY OF THE INVENTION

A unique foldable table (having an automatic button-latching and button-releasing system, an automatic leg-centering system, and an automatic collapse-preventing system) comprises a collapse-preventing tabletop assembly, a plurality of extendable-leg assemblies, and a plurality of scissoring-arm assemblies. The scissoring-arm assemblies are attached to the extendable-leg assemblies, respectively. The extendable-leg assemblies are releasably attached to the collapse-preventing tabletop assembly.

The extendable-leg assemblies have an automatic button-latching and button-releasing system and an automatic leg-centering system. The automatic button-latching and button-releasing system has unique spring-loaded latches for automatically latching and automatically releasing the release buttons of the unique foldable table to simplify all conventionally cumbersome, two-handed operations into uniquely easy, one-handed operations. The automatic leg-centering system has unique leg-centering clamps for automatically centering and clamping the extendable-leg assemblies to prevent the extendable-leg assemblies from wobbling.

The collapse-preventing tabletop assembly has an automatic collapse-preventing system. The automatic collapse-preventing system has unique collapse-preventing clamps for automatically cross-interlocking the tabletop and the extendable-leg assemblies to prevent the unique foldable table from folding inwards and, thus, collapsing, to strengthen the whole structure of the unique foldable table, to increase the tolerance, durability, and lifespan of the unique foldable table, and to eliminate the risk of personal injury.

UNIQUE AUTOMATIC FUNCTIONS

FIG. 1A illustrates all the automatic functions performed by a unique foldable table having an automatic button-latching and button-releasing system, an automatic leg-centering system, and an automatic collapse-preventing system. The unique foldable table (offering unique advantages of a new, convenient, easy-to-operate, and safe foldable table) performs all the following automatic functions:

5

- 1) Four automatic collapse-preventing functions **34a**, **34b**, **34c**, and **34d** at its first tabletop corner.
- 2) Four automatic collapse-preventing functions **35a**, **35b**, **35c**, and **35d** at its second tabletop corner.
- 3) Four automatic collapse-preventing functions **36a**, **36b**, **36c**, and **36d** at its third tabletop corner.
- 4) Four automatic collapse-preventing functions **37a**, **37b**, **37c**, and **37d** at its fourth tabletop corner.
- 5) Four automatic button-latching and button-releasing functions **38a**, **38b**, **39a**, and **39b** at its first locking sleeve.
- 6) Four automatic button-latching and button-releasing functions **40a**, **40b**, **41a**, and **41b** at its second locking sleeve.
- 7) Four automatic button-latching and button-releasing functions **42a**, **42b**, **43a**, and **43b** at its third locking sleeve.
- 8) Four automatic button-latching and button-releasing functions **44a**, **44b**, **45a**, and **45b** at its fourth locking sleeve.
- 9) Four automatic leg-centering functions **46a**, **46b**, **46c**, and **46d** at its first leg-centering clamp.
- 10) Four automatic leg-centering functions **47a**, **47b**, **47c**, and **47d** at its second leg-centering clamp.
- 11) Four automatic leg-centering functions **48a**, **48b**, **48c**, and **48d** at its third leg-centering clamp.
- 12) Four automatic leg-centering functions **49a**, **49b**, **49c**, and **49d** at its fourth leg-centering clamp.

PREFERRED EMBODIMENT

Structure and Function

FIGS. 1B, 2, 3, 4A, and 4B illustrate a unique foldable table **50**, having an automatic button-latching and button-releasing system, an automatic leg-centering system, and an automatic collapse-preventing system. Unique foldable table **50** comprises a collapse-preventing tabletop **51**, a first extendable-leg assembly **52**, a second extendable-leg assembly **53**, a third extendable-leg assembly **54**, a fourth extendable-leg assembly **55**, a first scissoring-arm assembly **56**, a second scissoring-arm assembly **57**, a third scissoring-arm assembly **58**, and a fourth scissoring-arm assembly **59**.

Collapse-preventing tabletop **51** comprises a tabletop frame **60**, a sheet of material **61**, and a plurality of collapse-preventing clamps **62a**, **63a**, **64a**, and **65a** having collapse-preventing lead-in edges **62b**, **63b**, **64b**, and **65b**, respectively. Sheet of material **61** is welded to tabletop frame **60**. Collapse-preventing clamps **62a**, **63a**, **64a**, and **65a** are welded to the inner surfaces of the four corners of tabletop frame **60**, respectively. Collapse-preventing clamps **62a**, **63a**, **64a**, and **65a** are for clamping on the frame of unique foldable table **50** to automatically cross-interlock the frame of unique foldable table **50** to prevent the frame from folding inwards and, thus, collapsing. Collapse-preventing lead-in edges **62b**, **63b**, **64b**, and **65b** are for leading collapse-preventing clamps **62a**, **63a**, **64a**, and **65a** into predetermined clamping positions, respectively.

First extendable-leg assembly **52** comprises a screw **66**, a tabletop-locking post **67**, a leg cap **68**, a leg **69**, a locking-peg leaf spring **70**, a locking peg **71**, a locking sleeve **72**, a leg-centering clamp **73**, a spring-loaded extendable-leg lock **74**, an extendable leg **75**, and an extendable-leg foot **76**.

Tabletop-locking post **67** has a threaded hole **77** mated to screw **66** for screw **66** to screw into. Tabletop-locking post **67** is integrated into leg cap **68**. Screw **66** is screwed into threaded hole **77**. Tabletop-locking post **67** is for one of collapse-preventing clamps **62a**, **63a**, **64a**, and **65a** of table-

6

top **51** to clamp on to automatically cross-interlock the frame of unique foldable table **50** to prevent the frame from folding inwards and, thus, collapsing.

Leg cap **68** is attached to the top end of leg **69**. Leg cap **68** is for connecting one of first, second, third, and fourth extendable-leg assemblies **52**, **53**, **54**, and **55** with two of first, second, third, and fourth scissoring-arm assemblies **56**, **57**, **58**, and **59**.

FIG. 5 illustrates leg **69** and locking sleeve **72**. Leg **69** has a locking-peg opening **78**, a latch-activating opening **79**, and a latch-deactivating edge **80**. Locking-peg leaf spring **70** is attached to locking peg **71**. Locking-peg leaf spring **70** and locking peg **71** are inserted into leg **69** such that the spring force of locking-peg leaf spring **70** pushes locking peg **71** outwards through locking-peg opening **78**. Locking peg **71** is for springing into a recess in locking sleeve **72** to secure locking sleeve **72**. Locking sleeve **72** is slidably attached to leg **69**.

FIGS. 6 and 7 illustrate perspective and hatching views of leg-centering clamp **73**. Leg-centering clamp **73** has a plurality of predetermined clamping jaws **81a** and a plurality of clamping lead-in edges **81b**. Clamping jaws **81a** are disposed at predetermined locations thereon, and capable of automatically centering and clamping extendable leg **75** to strengthen and prevent extendable leg **75** from wobbling. Leg-centering clamp **73** is snapped on the bottom end of leg **69**. Leg-centering clamp **73** is for automatically centering and clamping extendable leg **75** to strengthen and prevent extendable leg **75** from wobbling. Spring-loaded extendable-leg lock **74** is integrated into leg-centering clamp **73**. Spring-loaded extendable-leg lock **74** is for locking extendable leg **75** in place.

Extendable leg **75** has a plurality of extendable-leg-locking openings **82**. Extendable leg **75** is inserted into leg **69**. Extendable leg **75** is able to extend or retract to adjust the height of unique foldable table **50**. Each of extendable-leg-locking openings **82** is disposed at a predetermined location on extendable leg **75**. Each of extendable-leg-locking openings **82** is for extendable-leg lock **74** to be inserted into to lock extendable leg **75** in place. Extendable-leg foot **76** is screwed into the bottom end of extendable leg **75**. Extendable-leg foot **76** is for stabilizing unique foldable table **50** when set on a surface.

FIGS. 8A, 8B, 9A, and 9B illustrate locking sleeve **72**. Locking sleeve **72** has a spring-loaded button **83a**, a button groove **83b**, and a spring-loaded J-shaped latch **84**. Spring-loaded J-shaped latch **84** is pivotably attached to locking sleeve **72**. Spring-loaded J-shaped latch **84** has a latch head **85** and a latch tail **86**:

- a) Latch head **85** is for automatically latching onto spring-loaded button **83a** in the directions of arrows **87a** and **87b** when spring-loaded button **83a** is pressed in the direction of arrow **88**, to lock spring-loaded button **83a** in place (FIGS. 8A and 8B).
  - b) Latch tail **86** is for automatically releasing spring-loaded button **83a** in the directions of arrows **89a** and **89b** (when locking sleeve **72** slides down in the direction of arrow **91**, causing latch-deactivating edge **80** to automatically lift up and rotate latch tail **86** in the directions of arrows **89a** and **89b**) to return spring-loaded button **83a** back to its original position in the direction of arrow **90** when locking sleeve **72** is pushed downward in the direction of arrow **91** (FIGS. 9A and 9B).
- Locking sleeve **72** is for connecting and releasably locking together one of first, second, third, and fourth extendable-leg assemblies **52**, **53**, **54**, and **55** and two of first, second, third, and fourth scissoring-arm assemblies **56**, **57**, **58**, and **59**.

First, second, third, and fourth extendable-leg assemblies **52**, **53**, **54**, and **55** each are identical to and function like the others.

Each of first, second, third, and fourth scissoring-arm assemblies **56**, **57**, **58**, and **59** comprises a plurality of scissoring arms, screws, and nuts. By using the screws and nuts, the scissoring arms are connected to one another and to first, second, third, and fourth extendable-leg assemblies **52**, **53**, **54**, and **55**, respectively, as illustrated in FIG. 1, such that first, second, third, and fourth scissoring-arm assemblies **56**, **57**, **58**, and **59** can contract and expand to allow first, second, third, and fourth extendable-leg assemblies **52**, **53**, **54**, and **55** to fold and unfold, respectively.

First and third scissoring-arm assemblies **56** and **58** each are identical to and function like the other. Second and fourth scissoring-arm assemblies **57** and **59** each are identical to and function like the other.

Material

The components of unique foldable table **50**, each independently from the others, can be made of or made from rigid material(s), non-rigid material(s), flexible material(s), non-flexible material(s), resilient material(s), non-resilient material(s), elastic material(s), non-elastic material(s), or a combination of at least two of the above. For example, any of the components of unique foldable table **50** can be made of or made from plasticized material(s), metallic material(s), or a combination of the above. For another example, any of the components of unique foldable table **50** can be made of plastic, ABC, PVC, fiber class, iron, copper, zinc, bronze, tin, alloy, aluminum, stainless steel, the like, the equivalent, or a combination of at least two of the above. For another example, clamping jaws **81a** of leg-centering clamp **73** can be made of or made from semi-rigid or semi-resilient material(s), such that clamping jaws **81a** can clamp and center extendable leg **75**, within leg **69**. For another example, leg-centering clamp **73** can be made of or made from plastic, plasticized material(s), the like, or the equivalent.

Operation

The unique foldable table has the automatic button-latching and button-releasing system, the automatic leg-centering system, and the automatic collapse-preventing system. Referring to FIGS. 8A, 8B, 9A, 9B, and 10:

A) To Unfold Unique Foldable Table **50** from a Folded Position:

Pulling outwards first, second, third, and fourth extendable-leg assemblies **52**, **53**, **54**, and **55**;

Sliding upwards locking sleeve **72** and other identical locking sleeves of first, second, third, and fourth extendable-leg assemblies **52**, **53**, **54**, and **55**, respectively, until locking peg **71** and other identical locking pegs of first, second, third, and fourth extendable-leg assemblies **52**, **53**, **54**, and **55** snap-lock locking sleeve **72** and other identical locking sleeves of first, second, third, and fourth extendable-leg assemblies **52**, **53**, **54**, and **55**, respectively, to lock first, second, third, and fourth extendable-leg assemblies **52**, **53**, **54**, and **55** and first, second, third, and fourth scissoring-arm assemblies **56**, **57**, **58**, and **59** in place; and

Installing collapse-preventing tabletop **51** on leg cap **68** and other identical leg caps of first, second, third, and fourth extendable-leg assemblies **52**, **53**, **54**, and **55** such that collapse-preventing lead-in edges **62b**, **63b**, **64b**, and **65b** lead collapse-preventing clamps **62a**, **63a**, **64a**, and **65a** into predetermined clamping positions, and such that collapse-preventing clamps **62a**, **63a**, **64a**, and **65a** clamp on tabletop-locking post **67** and other identical tabletop-locking posts of first, second, third, and fourth extendable-leg assemblies **52**, **53**, **54**, and **55**, respectively, to automatically cross-interlock

first, second, third, and fourth extendable-leg assemblies **52**, **53**, **54**, and **55** and first, second, third, and fourth scissoring-arm assemblies **56**, **57**, **58**, and **59**.

As a Result:

- 1) The automatic collapse-preventing system automatically cross-interlocks first, second, third, and fourth extendable-leg assemblies **52**, **53**, **54** and **55** and first, second, third, and fourth scissoring-arm assemblies **56**, **57**, **58**, and **59** to prevent them from accidentally folding inwards in the directions of arrows **62c**, **63c**, **64c**, and **65c** (FIG. 4A) and, thus, to prevent them from collapsing while in use; and
- 2) The automatic leg-centering system automatically centers and clamps extendable leg **75** and other identical extendable legs of first, second, third, and fourth extendable-leg assemblies **52**, **53**, **54**, and **55** in the directions of arrows **92a**, **92b**, **92c**, and **92d** (FIG. 10) to prevent extendable leg **75** and the other identical extendable legs from wobbling.

B) To Fold Up Unique Foldable Table **50** from an Unfolded Position:

Lifting collapse-preventing tabletop **51** off of leg cap **68** and the other identical leg caps.

Pressing spring-loaded button **83a** (FIGS. 8A and 8B), in the direction of arrow **88**, and other identical spring-loaded buttons of first, second, third, and fourth extendable-leg assemblies **52**, **53**, **54**, and **55** to press locking peg **71** and other identical locking pegs of first, second, third, and fourth extendable-leg assemblies **52**, **53**, **54**, and **55** out of locking sleeve **72** and the other identical locking sleeves, respectively, until latch head **85** and other identical latch heads of first, second, third, and fourth extendable-leg assemblies **52**, **53**, **54**, and **55** automatically snap into button groove **83b** and other identical button grooves of first, second, third, and fourth extendable-leg assemblies **52**, **53**, **54**, and **55** and latch on spring-loaded button **83a** and the other identical spring-loaded buttons (FIGS. 8A and 8B), in the directions of arrows **87a** and **87b**, respectively, and until latch tail **86** and other identical latch tails of first, second, third, and fourth extendable-leg assemblies **52**, **53**, **54**, and **55** automatically rotate into latch-activating opening **79** and other identical latch-activating openings of first, second, third, and fourth extendable-leg assemblies **52**, **53**, **54**, and **55**; and

Folding inwards first, second, third, and fourth extendable-leg assemblies **52**, **53**, **54** and **55** to slide downwards latch tail **86** and the other identical latch tails (FIGS. 9A and 9B), in the direction of arrow **91**, until latch-deactivating edge **80** and other identical latch-deactivating edges of first, second, third, and fourth extendable-leg assemblies **52**, **53**, **54**, and **55** automatically lift up and rotate latch tail **86** and the other identical latch tails (FIGS. 9A and 9B), in the direction of arrow **89a**, to automatically rotate latch head **85** and the other identical latch heads downwards (FIGS. 9A and 9B), in the direction of arrow **89b**, and until latch head **85** and the other identical latch heads automatically release spring-loaded button **83a**, in the direction of arrow **90**, and the other identical spring-loaded buttons, respectively, and spring-loaded button **83a** and the other identical spring-loaded buttons return back to their original positions (FIGS. 9A and 9B), which automatically rotate latch tail **86** and the other identical latch tails upwards and away further from latch-deactivating edge **80** and the other identical latch-deactivating edges, respectively (for example, to prevent latch tail **86** and the other identical latch tails from scratching other components of unique foldable table **50**).

As a Result:

- 1) The automatic button-latching and button-releasing system automatically latches on, automatically releases, and automatically resets spring-loaded button **83a** and the other

- identical spring-loaded buttons to turn a cumbersome, two-handed operation into an easy, one-handed operation; and
- 2) The automatic button-latching and button-releasing system eliminates the simultaneous needs for using one hand to press spring-loaded button **83a** and the other identical spring-loaded buttons while using another hand to stretch the table frame, at the same time, to unlock the table frame.
- C) To Adjust the Height of Unique Foldable Table **50**:
- Pulling on extendable-leg lock **74** (FIG. 10) and other identical extendable-leg locks of first, second, third, and fourth extendable-leg assemblies **52**, **53**, **54**, and **55** until extendable leg **75** and the other identical extendable legs are unlocked, respectively;

Pulling extendable leg **75** and the other identical extendable legs downwards to raise unique foldable table **50** to a desired height; and

Pressing extendable-leg lock **74** and the other identical extendable-leg locks back into one of extendable-leg-locking openings **82** and ones of other identical extendable-leg-locking openings of first, second, third, and fourth extendable-leg assemblies **52**, **53**, **54**, and **55** until extendable leg **75** and the other identical extendable legs are locked, respectively.

As a Result:

- 1) The automatic leg-centering system automatically centers and clamps extendable leg **75** and the other identical extendable legs to prevent extendable leg **75** and the other identical extendable legs from wobbling while in use; and
- 2) The automatic leg-centering system automatically strengthens first, second, third, and fourth extendable-leg assemblies **52**, **53**, **54**, and **55**, and thus automatically strengthens the whole structure of unique foldable table **50** while in use for substantially higher degrees of tolerance and durability.

FIG. 11 illustrates a spring clamp **93** and a tabletop-locking post **94**. Spring clamp **93** is equivalent to, functions similarly to, and can replace collapse-preventing clamp **65a** in the first example above (FIG. 4B). The two opposite ends of spring clamp **93** are snapped into the two opposite openings at the corner of tabletop frame **60** to be attached thereto. Tabletop-locking post **94** is equivalent to, functions similarly to, and can replace tabletop-locking post **67** in the first example above (FIG. 4B). Tabletop-locking post **94** has a circular groove **95** for spring clamp **93** to snap therein to be releasably secured therein when installing collapse-preventing tabletop **51** on first, second, third, and fourth extendable-leg assemblies **52**, **53**, **54**, and **55**.

Majors Advantages

The present invention substantially departs from the conventional concepts and designs of the prior art. In doing so, the present invention provides a unique foldable table having many unique and significant features, automatic functions, and advantages, which overcome all the disadvantages of the prior art, as follows:

It is an object of the present invention to provide the unique foldable table having an automatic button-latching and button-releasing system, an automatic leg-centering system, and an automatic collapse-preventing system.

It is another object of the present invention to provide the automatic button-latching and button-releasing system for automatically latching the release buttons of the unique foldable table, and for automatically releasing the release buttons of the unique foldable table. The automatic button-latching and button-releasing system can be automatically activated whenever the buttons are pressed, and can be automatically deactivated whenever the table is folded.

It is a further object of the present invention to provide the automatic button-latching and button-releasing system for

eliminating the simultaneous needs for using one hand to press the release buttons while using another hand to stretch the frames of the prior-art tables to unlock the prior-art tables at the same time.

It is an even further object of the present invention to provide the automatic button-latching and button-releasing system for simplifying a conventionally cumbersome, two-handed operation of folding the prior-art tables into a uniquely easy, one-handed operation, which requires only one simple push for each of the release buttons.

It is another object of the present invention to provide the automatic button-latching and button-releasing system for eliminating the needs for stretching the frames of the prior-art tables while unlocking the prior-art tables to offer ease of use, safety, and durability, and to eliminate the risk of personal injury.

It is yet another object of the present invention to provide the automatic leg-centering system for automatically centering and clamping the extendable-leg assemblies of the unique foldable table to strengthen the extendable-leg assemblies to prevent them from wobbling while in use.

It is yet another object of the present invention to provide the automatic collapse-preventing system for automatically cross-interlocking the removable tabletop and the frame of the unique foldable table to prevent the frame from accidentally folding inwards and collapsing and, thus, to eliminate the risk of personal injury.

It is still yet another object of the present invention to provide the automatic collapse-preventing system for automatically cross-interlocking the removable tabletop and the frame of the unique foldable table to prevent the frame from twisting and stretching while in use to strengthen the whole structure of the unique foldable table while in use for substantially higher degrees of tolerance and durability.

UNIQUE AUTOMATIC FUNCTION

FIG. 12 is a duplicate of FIG. 1A, illustrating all the automatic functions performed by the unique foldable table having an automatic button-latching and button-releasing system, an automatic leg-centering system, and an automatic collapse-preventing system. The unique foldable table (offering unique advantages of a new, convenient, easy-to-operate, and safe foldable table) performs all the following automatic functions:

- 1) Four automatic collapse-preventing functions **34a**, **34b**, **34c**, and **34d** at its first tabletop corner.
- 2) Four automatic collapse-preventing functions **35a**, **35b**, **35c**, and **35d** at its second tabletop corner.
- 3) Four automatic collapse-preventing functions **36a**, **36b**, **36c**, and **36d** at its third tabletop corner.
- 4) Four automatic collapse-preventing functions **37a**, **37b**, **37c**, and **37d** at its fourth tabletop corner.
- 5) Four automatic button-latching and button-releasing functions **38a**, **38b**, **39a**, and **39b** at its first locking sleeve.
- 6) Four automatic button-latching and button-releasing functions **40a**, **40b**, **41a**, and **41b** at its second locking sleeve.
- 7) Four automatic button-latching and button-releasing functions **42a**, **42b**, **43a**, and **43b** at its third locking sleeve.
- 8) Four automatic button-latching and button-releasing functions **44a**, **44b**, **45a**, and **45b** at its fourth locking sleeve.
- 9) Four automatic leg-centering functions **46a**, **46b**, **46c**, and **46d** at its first leg-centering clamp.

11

- 10) Four automatic leg-centering functions **47a, 47b, 47c, and 47d** at its second leg-centering clamp.
- 11) Four automatic leg-centering functions **48a, 48b, 48c, and 48d** at its third leg-centering clamp.
- 12) Four automatic leg-centering functions **49a, 49b, 49c, and 49d** at its fourth leg-centering clamp.

CONCLUSION

Any component and the cross-section of any component of the unique foldable table can have any shape and size. The unique foldable table can have any number of any of its components, and can be used to support any type of weight, such as human or object. For example, FIG. 13 illustrates a round leg, round leg-centering clamp, and round extendable leg, which are equivalents of leg **69**, leg-centering clamp **73**, and extendable leg **75**. For another example, the unique foldable table can have more than four extendable-leg assemblies as illustrated in FIG. 14.

What is claimed is:

1. A foldable table comprising:
 a collapse-preventing top, said collapse-preventing top comprising a top frame, a sheet of material, and a plurality of collapse-preventing clamps, said sheet of material attached to said top frame, said top frame having a plurality of corners each of which has an inner surface, said collapse-preventing clamps attached to the inner surfaces of the four corners of said top frame by top-clamp-attaching means, respectively;
 a plurality of extendable-leg assemblies, each of said extendable-leg assemblies comprising a top-locking post, a leg cap, a leg, a locking-peg leaf spring, a locking peg, a locking sleeve, a leg-centering clamp, a spring-loaded extendable-leg lock, an extendable leg, and an extendable-leg foot, said top-locking post integrated into said leg cap, said top-locking post for one of said collapse-preventing clamps of said collapse-preventing top to clamp on to interlock said extendable-leg assemblies, said leg cap attached to an end of said leg, said leg having a locking-peg opening, said locking-peg leaf spring integrated into said locking peg, said locking-peg leaf spring and said locking peg inserted into said leg such that the spring force of said locking-peg leaf spring pushes said locking peg through said locking-peg opening, said locking sleeve slid on said leg such that said locking sleeve is slidably attached to said leg, said locking sleeve having a recess, said recess for said locking peg to be pressed into to secure said locking sleeve when said recess slides over said locking peg, said leg-centering clamp having a plurality of predetermined clamping jaws, said leg-centering clamp having a ring-like edge and an invisible longitudinal central axis, said clamping jaws molded to and along said ring-like edge of said leg-centering clamp such that said clamping jaws surround and lean inward toward said invisible central axis of said leg-centering clamp at a predetermined angle creating a force for said clamping jaws to center said extendable leg, said leg-centering clamp attached to another end of said leg by centering-clamp-attaching means, said spring-loaded extendable-leg lock integrated into said leg-centering clamp, said extendable leg inserted into said leg-centering clamp and said leg, said extendable leg capable of extending and retracting to adjust the height of said foldable table, said extendable leg having a plurality of extendable-leg-locking openings, each of said extendable-leg-locking openings disposed at a predetermined location on said extendable leg, each of said extendable-leg-locking openings for said extendable-leg lock to be pressed into to lock said extendable leg at a predetermined location inside said leg, said extendable-leg foot attached to an end of said extendable leg by foot-attaching means, said extendable-leg foot for stabilizing said foldable table when set on a surface; and
 a plurality of scissoring-arm assemblies, each of said scissoring-arm assemblies comprising a plurality of scissoring arms, a plurality of screws, and a plurality of nuts, said scissoring arms pivotally connected to one another in a scissoring configuration and to said leg caps and said locking sleeves of said extendable-leg assemblies by said screws and said nuts, respectively, such that said scissoring-arm assemblies can contract and expand to allow said foldable table to fold and unfold, respectively, said locking sleeve having a spring-loaded button and a spring-loaded latch, said spring-loaded button having a button groove, said leg further having a latch-activating opening and a latch-deactivating edge, said spring-loaded latch pivotably attached to said locking sleeve, said spring-loaded latch for rotating into said button groove and into said latch-activating opening to latch on said spring-loaded button when said spring-loaded button is pressed, said latch-deactivating edge of said latch-activating opening for rotating said spring-loaded latch out of said button groove and out of said latch-activating opening to release said spring-loaded button when said foldable table is folded,
- whereby, provided is said foldable table, which:
 automatically latches on said spring-loaded buttons when said spring-loaded buttons is pressed,
 automatically releases said spring-loaded buttons when said foldable table is folded,
 automatically centers said extendable leg when said extendable leg is locked, and
 automatically interlocks said extendable-leg assemblies when said collapse-preventing top is installed thereon.
2. The foldable table of claim 1, further, comprising a plurality of screws, said screws for screwing into said top-locking posts to strengthen said top-locking posts, respectively.
3. The foldable table of claim 2, wherein, said sheet of material having a plurality of openings and two opposite surfaces, each of said openings extending from one of said opposite surfaces to another one of said opposite surfaces.
4. The foldable table of claim 1, wherein, having four extendable-leg assemblies.
5. The foldable table of claim 1, wherein, having more than four extendable-leg assemblies.
6. The foldable table of claim 1, wherein, said collapse-preventing top being rectangular.
7. The foldable table of claim 1, wherein, said collapse-preventing top being square.
8. The foldable table of claim 1, wherein, said collapse-preventing top being round.
9. The foldable table of claim 1, wherein, each of said spring-loaded latches being a wire.
10. The foldable table of claim 1, wherein, each of said spring-loaded latches made of metallic material.
11. The foldable table of claim 1, wherein, each of said spring-loaded latches made of plasticized material.
12. A foldable table comprising:
 an interlocking top, said interlocking top comprising a frame, a sheet of material, and a plurality of interlocking clamps, said sheet of material attached to said frame by

13

sheet-attaching means, said frame having four corners each of which has an inner surface, said interlocking clamps attached to the inner surfaces of the four corners of said frame by interlocking-clamp-attaching means, respectively;

a plurality of extendable assemblies, each of said extendable assemblies comprising

a locking post, a cap, a supporting member, a spring, a peg, a sleeve, a centering clamp, a spring-loaded locking means, an extendable supporting member, and a stabilizing means, said locking post integrated into said cap, said locking post for one of said interlocking clamps of said interlocking top to clamp on to interlock said extendable assemblies, said cap attached to an end of said supporting member, said supporting member having a locking opening, said spring integrated into said peg, said spring and said peg inserted into said supporting member such that the spring force of said spring pushes said peg through said locking opening, said sleeve slid on said supporting member such that said sleeve is slidably attached to said supporting member, said sleeve having a recess, said recess for said peg to be pressed into to secure said sleeve when said recess slides over said peg, said centering clamp having a plurality of predetermined clamping jaws, said leg-centering clamp having a ring-like edge and an invisible longitudinal central axis said clamping jaws molded to and along said ring-like edge of said leg-centering clamp such that said clamping jaws surround and lean inward toward said invisible central axis of said leg-centering clamp at a predetermined angle creating a force for said clamping jaws to center said extendable leg, said centering clamp attached to another end of said supporting member by centering-clamp-attaching means, said spring-loaded locking means integrated into said centering clamp, said extendable supporting member inserted into said centering clamp and said supporting member, said extendable supporting member capable of extending and retracting to adjust the height of said foldable table, said extendable supporting member having a plurality of securing openings, each of said securing openings disposed at a predetermined location on said extendable supporting member, each of said securing openings for said extendable-leg lock to be pressed into to lock said extendable supporting member at a predetermined location inside said supporting member, said stabilizing means attached to an end of said extendable supporting member by stabilizer attaching means, said stabilizing means for stabilizing said foldable table when set on a surface; and

a plurality of foldable assemblies, each of said foldable assemblies comprising a plurality of foldable members and foldable attaching means, said foldable members pivotally connected to one another in a scissoring configuration and to said caps and said sleeves of said extendable assemblies by said foldable attaching means, respectively, such that said foldable assemblies can contract and expand to allow said foldable table to fold and unfold, respectively, said sleeve having a spring-loaded button and a spring-loaded latching means, said spring-loaded button having a groove, said supporting member further having a latching opening and an unlatching edge, said spring-loaded latching means pivotably attached to said sleeve, said spring-loaded latching means for rotating into said groove of said spring-loaded button and into said latching opening to latch on said

14

spring-loaded button when said spring-loaded button is pressed, said unlatching edge of said latching opening for rotating said spring-loaded latching means out of said groove of said spring-loaded button and out of said latching opening to release said spring-loaded button when said foldable table is folded,

whereby, provided is said foldable table, which:

automatically latches on said spring-loaded buttons when said spring-loaded buttons are pressed,

automatically releases said spring-loaded buttons when said foldable table is folded,

automatically centers said extendable supporting members when said extendable supporting members are locked, and

automatically interlocks said extendable assemblies when said interlocking top is installed thereon.

13. The foldable table of claim 12, further, comprising a plurality of screws, said screws for screwing into said top-locking posts to strengthen said top-locking posts, respectively.

14. The foldable table of claim 13, wherein, said sheet of material having a plurality of openings and two opposite surfaces, each of said openings extending from one of said opposite surfaces to another one of said opposite surfaces.

15. The foldable table of claim 12, wherein, each of said spring-loaded latches being a molded or stamped latch.

16. The foldable table of claim 12, wherein, each of said spring-loaded latches made of metallic material.

17. The foldable table of claim 12, wherein, each of said spring-loaded latches made of plasticized material.

18. The foldable table of claim 12, wherein, having four extendable-leg assemblies.

19. The foldable table of claim 12, wherein, having more than four extendable-leg assemblies.

20. A foldable table comprising an interlocking top, a plurality of extendable assemblies, and a plurality of foldable assemblies, said interlocking top comprising a frame, a sheet of material, and a plurality of interlocking clamps, said sheet of material attached to said frame by sheet-attaching means, said frame having four corners each of which has an inner surface, said interlocking clamps attached to the inner surfaces of the four corners of said frame by interlocking-clamp-attaching means, respectively, each of said extendable assemblies comprising a locking post, a cap, a supporting member, a spring, a peg, a sleeve, a centering clamp, a spring-loaded locking means, an extendable supporting member, and a stabilizing means, said locking post integrated into said cap, said locking post for one of said interlocking clamps of said interlocking top to clamp on to interlock said extendable assemblies, said cap attached to an end of said supporting member, said supporting member having a locking opening, said spring integrated into said peg, said spring and said peg inserted into said supporting member such that the spring force of said spring pushes said peg through said locking opening, said sleeve slid on said supporting member such that said sleeve is slidably attached to said supporting member, said sleeve having a recess, said recess for said peg to be pressed into to secure said sleeve when said recess slides over said peg, said

centering clamp having a plurality of predetermined clamping jaws, said leg-centering clamp having a ring-like edge and an invisible longitudinal central axis, said clamping jaws molded to and along said ring-like edge of said leg-centering clamp such that said clamping jaws surround and lean inward toward said invisible central axis of said leg-centering clamp at a predetermined angle creating a force for said clamping jaws to center

15

said extendable leg, said centering clamp attached to another end of said supporting member by centering-clamp-attaching means, said spring-loaded locking means integrated into said centering clamp, said extendable supporting member inserted into said centering clamp and said supporting member, said extendable supporting member capable of extending and retracting to adjust the height of said foldable table, said extendable supporting member having a plurality of securing openings, each of said securing openings disposed at a predetermined location on said extendable supporting member, each of said securing openings for said extendable-leg lock to be pressed into to lock said extendable supporting member at a predetermined location inside said supporting member, said stabilizing means attached to an end of said extendable supporting member by stabilizer attaching means, said stabilizing means for stabilizing said foldable table when set on a surface, each of said foldable assemblies comprising a plurality of foldable members and foldable attaching means, said foldable members pivotally connected to one another in a scissoring configuration and to said caps and said sleeves of said extendable assemblies by said foldable attaching means, respectively, such that said foldable assemblies can contract and expand to allow said fold-

5

10

15

20

16

able table to fold and unfold, respectively, said sleeve having a spring-loaded button and a spring-loaded latching means, said spring-loaded button having a groove, said supporting member further having a latching opening and a unlatching edge, said spring-loaded latching means pivotably attached to said sleeve, said spring-loaded latching means for rotating into said groove of said spring-loaded button and into said latching opening to latch on said spring-loaded button when said spring-loaded button is pressed, said unlatching edge of said latching opening for rotating said spring-loaded latching means out of said groove of said spring-loaded button and out of said latching opening to release said spring-loaded button when said foldable table is folded, whereby, provided is said foldable table, which automatically latches on said spring-loaded buttons when said spring-loaded buttons are pressed, automatically releases said spring-loaded buttons when said foldable table is folded, automatically centers said extendable supporting members when said extendable supporting members are locked, and automatically interlocks said extendable assemblies when said interlocking top is installed thereon.
